UNITED STATES PATENT OFFICE.

EDWIN W. LEAGUE, OF PLYMOUTH, INDIANA.

TROUSERS-SUPPORTER.

1,381,654.

Specification of Letters Patent. Patented Feb. 24, 1920.

Application filed August 20, 1919. Serial No. 318,685.

To all whom it may concern:

Be it known that I, EDWIN W. LEAGUE, a citizen of the United States, residing at Plymouth, in the county of Marshall and 5 State of Indiana, have invented certain new and useful Improvements in Trousers-Supporters; and I do hereby declare the following to be a full, clear, and exact description of the invention, such as will enable others 10 skilled in the art to which it appertains to make and use the same.

The present invention relates to garment supporters, and aims to provide a novel and improved trouser supporter of simple and 15 inexpensive construction, which will be invisible, as it can be worn under the shirt, and which will also serve to efficiently support the trousers.

Another object is the provision of such a 20 device which has portions to extend from below the lower edge of the shirt on both inside and outside thereof, for suspending the trousers in an efficient and practical manner.

A further object is the provision of such 25 a device having means whereby it will also serve to hold down the shirt within the trousers.

A still further object is the provision of a 30 device of the nature indicated which can be cheaply and easily manufactured from sheets of celluloid, metal or other suitable material.

With the foregoing and other objects in 35 view, which will be apparent as the description proceeds, the invention resides in the construction and arrangement of parts hereinafter described and claimed, it being understood that changes can be made within the scope of what is claimed without departing 40 from the spirit of the invention.

The invention is illustrated in the accompanying drawing, wherein:—

Figure 1 is a face view of the supporter.

Fig. 2 is an edge view thereof as applied.

In carrying out the invention, the supporter is struck from a sheet of celluloid, sheet metal, or other suitable resilient material, and comprises a flat vertical shank or stem 1, the upper end portion of which is 45 enlarged and bifurcated so as to have the laterally spaced upwardly projecting lobes or portions 2 provided with the transverse slots 3 at their upper ends for the attachment of the ends of a shoulder strap or elastic 50 4, which can extend over the shoulder in the form of a loop, suspending the supporter 55 at the side of the hip. The recess or slot between the lobes 2 enables said lobes to flex and fit the body.

The device is provided at the opposite 60 edges of the shank or stem 1 with a pair of upwardly extending supporting arms or stems 5, which are also flat, said portions of the device being arranged edge to edge. The lower ends of the shank 1 and arms 5 merge 65 together, as at 6, whereby said arms are supported in upwardly extending position from the lower end of the shank 1 which is suspended from the shoulder strap 4. The upper end portions of the arms 5 diverge apart 70 upwardly along the diverging edges of the lobes 2, and the upper ends of said arms have upwardly opening notches or slots 8 for receiving the buttons B which are sewed to the inside of the trousers T. 75

In wearing the supporter, one being used at each side of the body at the inside of the trousers, the shirt S extends downwardly between the shank 1 and arms 5 with said shank extending upwardly on the inner side 80 of the shirt so that the shoulder strap or suspender 4 will be concealed under the shirt. The arms 5 extend upwardly on the exterior 85 of the shirt within the trousers, so as to be concealed from view, and the buttons B of the trousers can be seated in the notches 8, thereby supporting the upper edge of the trousers from the upper ends of the arms 5. The device is preferably shaped or bent so 90 as to fit the side of the body, and the arms 5 will hold the trousers in place, but can flex outwardly for convenience. By wearing a pair of the supporters with a pair of buttons on the interior of the trousers, at each side, engaging the arms 5 at the opposite sides of 95 the shank 1, the trousers will be supported at four points in an efficient and convenient manner. The shirt extends downwardly between the shank 1 and arms 5 of the supporter, as seen in Fig. 2, so that the supporter extends downwardly underneath the lower edge of the shirt, to avoid injury to or tearing of the fabric.

In order that the device will also hold the shirt down, within the trousers, the lower 105 end portion of the shank 1 is slightly enlarged or widened, so as to have the convexed curved portions 9 at the opposite edges, and the lower end portions of the arms 5 are similarly curved, as at 10. Thus, 110 the slots 11 between the shank 1 and arms 5 are curved apart at their lower ends. There-

fore, when the shirt is drawn downwardly in the lower ends of the slots 11, the material will be gripped between the edges of the portions 9 and 10, thereby resisting the material from pulling upwardly. In this way, the device will also serve to hold the shirt down within the trousers, to avoid the annoyance of the shirt coming out of the lower garment.

10 Having thus described the invention, what is claimed as new is:—

15 1. A trouser supporter comprising three united portions extending upwardly side by side, means for suspending the central portion, and the other portions having means for supporting the trousers at their upper ends.

20 2. A trouser supporter comprising portions extending upwardly to be disposed at inner and outer sides of a shirt, means for suspending the inner portion, the outer portions having means for supporting the trousers, and said portions being formed to grip the shirt between them.

25 3. A trouser supporter comprising a shank having means at the upper end thereof for suspending it at the inner side of a shirt, arms extending upwardly from the lower end of said shank at the opposite sides thereof and having trouser supporting means at their upper ends.

30 4. A trouser supporter comprising a shank having means at the upper end thereof for suspending it at the inner side of a shirt, arms extending upwardly from the lower end of said shank at the opposite sides

thereof and having trouser supporting means at their upper ends, said shank and arms having portions for gripping the shirt between them.

40 5. A trouser supporter comprising a flat vertical shank having its upper end portion bifurcated, and provided with laterally spaced lobes, said lobes having slots for the connection of a suspending strap, and a pair 45 of flat upwardly extending arms united at their lower ends with the lower end of said shank and disposed at the opposite sides of said shank edge to edge, the upper end portions of said arms diverging upwardly 50 at the opposite edges of said lobes, and the upper ends of said arms having notches for supporting the trousers.

55 6. A trouser supporter comprising a flat vertical shank having means at the upper end thereof for suspending it at the inner side of a shirt, and a pair of flat upwardly extending arms at the opposite sides of said shank disposed edge to edge therewith, the lower ends of said shank and arms merging 60 together, the upper ends of said arms having means for supporting the trousers, and the adjacent edges of said shank and arms being curved at their lower ends for gripping the shirt between them.

65 In testimony whereof I have signed my name to this specification in the presence of two subscribing witnesses.

EDWIN W. LEAGUE.
